UNITED STATES PATENT OFFICE.

GEORGE J. McGANN, OF PROVIDENCE, RHODE ISLAND, ASSIGNOR TO SLASHER ROLLS CO., A CORPORATION OF MASSACHUSETTS.

TEXTILE PROCESSING OR FINISHING MACHINE.

Application filed March 26, 1925. Serial No. 18,546.

The invention relates to an improvement in slashers, starch mangles, dyeing machines and other machines for processing or finishing yarns and fabrics or other fibrous materials and which machines employ one or more covered rolls for effecting the processing or finishing operation.

The essential object of the invention is to provide means for applying a covering to any one or more of the rolls in the machine as the rolls are rotated in the operation of the machine; also, to provide means for renewing the covering on any roll without arresting the operation of the machine to remove the roll or to strip the old covering from it; also, to provide means for covering any roll while the machine is operating upon the work without impairing the quality of the work.

Another object of the invention is to eliminate the manual labor and skill required to cover a squeeze roll with a blanket as usually practised in the present art.

Incidentally to the objects above referred to, it is my further purpose to provide such roll covering as will be economical, durable and most efficient in effecting the processing or finishing operations incidental to the machine or rolls in connection with which the covering is used.

The manner and means for securing the above and further objects of the improvement are fully set forth in the following specification which describes a preferred embodiment of the invention as illustrated by the accompanying drawings. In the drawings:

Fig. 1 is a side view of a section of a sizing machine or slasher for slashing warps, showing the squeeze-rolls and the means for applying the covering thereto as embodied in the machine;

Fig. 2 is a detailed view of a portion of the machine, showing the means for applying the covering to the squeeze-rolls and for renewing the surface of the covering;

Fig. 3 is an enlarged end view of the roll-covering mechanism of the machine;

Fig. 4 is a detailed view of the strand-feeding means of the roll-covering mechanism;

Fig. 5 is an end view of a starch-mangle showing its roll-covering mechanism; and

Fig. 6 is a front view of the same.

Referring to Fig. 1 of the drawings, in

the embodiment of the invention as here shown the sizing machine or slasher section for slashing the warp yarns is organized as follows: Suitable end-frames or standards 2 support a size-vat 3 constructed in the form of a tank or trough. The size-vat 3 has end-members 4 provided with bearings for the end journals of two shafts 5 and 6 which carry the copper size-rolls 7 and 8 extending horizontally across the size-vat to adapt them to be partially immersed in the starch or sizing-fluid S contained therein. At one end of the shafts 5 and 6 are gears 9 and 10 meshing with a driving-gear 11 journaled on the end-member 4. The driving-gear 11 carries a bevel-gear 12 on its side from which it is driven through the means of a bevel-pinion 15 fast on a shaft 16. The shaft 16 is journaled in a bearing 17, attached to the side of the end-frame or standard 2, and extends to the right of the machine to adapt it to be connected with any suitable source of power. Usually the shaft 16 is connected to the winding-drum on the drying end of the slasher, not herein shown, to be driven from the power mechanism thereof.

At the receiving end of the machine are suitable guide-rollers 19 and 20 across which the warp yarns w lead as they feed into the size-vat 3 from the section-beams, not herein shown. The rollers 19 and 20 have trunnions 21 and 22 journaled in suitable bearings at the top of the end-members 4 of the vat. Within the vat 3 is an immersion-roll 23 having its end-gudgeons 24 supported from pendant arms 25 shown by dotted lines in Fig. 1. The arms 25 are connected at their upper ends to vertical racks 26 arranged at either end of the vat on the outside of the end-members 4. The racks 26 are adapted to slide up and down to raise and lower the immersion-roll 23 in the vat 3 to regulate its degree of submergence in the sizing-fluid S in accordance with the level thereof. The racks 26 are operated from pinions 27 at the ends of shafts 28 which are journaled in bearings 29 on the standards 2. The shafts 28 carry worm-gears 30 meshing with worms 31 on a horizontal cross-shaft 32. On the end of the shaft 32 is a hand-wheel 33 by means of which it may be manually rotated to turn the shafts 28 to raise and lower the racks 26 in accordance with the usual arrangement in machines of the present type. The warp yarns w draw

from the section-beams, not herein shown, across the guide-rolls 19 and 20, thence down under the immersion-roll 23 and up over the size-rolls 7 and 8, whence they lead to the 5 drying section of the machine. Above the size-rolls 7 and 8 are the squeeze-rolls 35 and 36 arranged with their peripheries bearing against the size-rolls. The squeeze-rolls 35 and 36 have journals 37 and 38 constituted by reduced portions of their axial 10 shafts 39 and 40, see also Fig. 2. The journals 37 and 38 are received in slotted bearings 41 and 42 formed as a part of and projecting upwardly from the end-members 4 15 of the size-vat 3.

In my new and improved construction of the squeeze-rolls I provide the barrels of the rolls with end-flanges or heads 43 and 44 which overlap the ends of the lower size- 20 rolls or drums 7 and 8. These flanges may be of relatively thin metal, preferably brass, and are employed to sustain and hold in place the roll-covering which is applied to the peripheral surface of the squeeze-rolls. 25 I also provide the squeeze-rolls 35 and 36 with spur-gears 45 and 46 mounted fast on their shafts 39 and 40 at the side of their end-flanges. The gears 45 and 46 serve as 30 means for connecting the squeeze-rolls to drive the mechanism which applies the outer surface-covering to the barrels of the rolls.

As shown more particularly in Figs. 2 and 3, the present improved mechanism for applying the covering to the squeeze-rolls comprises means for winding onto the barrel of the rolls one or more layers of strands of textile material such as cotton or worsted yarns. Preferably, I employ cotton yarn for the covering of the first roll 35 and worsted 35 yarn for the finishing-roll 36, but it is to be understood that the character of the covering material may be varied in accordance with conditions and the results desired. In accordance with the preferred practice, the barrels of the squeeze-rolls are first covered with a layer of relatively flexible or resilient material, such as soft felt, before the textile strands are applied thereto. As shown in Fig. 2, a strip of felt γ is first wound spirally 40 of the barrel of the squeeze-roll 35 with its edges abutting to provide a smooth, unbroken surface. The strip of felt γ has its ends cut to match the spiral winding so that they do not overlap where they terminate 45 at the end-flanges or heads 43 of the roll. The method of cutting, laying and matching the felt strip on the barrel of the roll is more fully described in my companion application for U. S. Letters Patent, Serial 60 No. 18,547, filed concurrently herewith; the present application relating more particularly to the means and mechanism for applying the surface covering to the roll. To apply this surface covering of strands over 65 the layer of felt on the barrel of the roll I

make use of a strand-laying mechanism which is organized with the operating mechanism of the machine as next explained.

The strand-laying mechanism is designed to adapt it to be built into machines of 70 standard type to serve as a permanent part thereof. To support the strand-laying mechanism from the machine I may employ any suitable form of brackets or standards mounted on the main frame thereof. As 75 shown in Figs. 1 and 2, I attach to the end-members 4 of the size-vat 3 a pair of brackets or arms 50 of inverted L-shape which are fastened in place by means of bolts 51. At the forward ends of the arms 50 are elongated hubs or bearings 52, in which is journaled a rotatable screw-shaft 53. The screw-shaft 53 is held in its bearings 52 by end-collars 54 secured in place by suitable means such as the set-screws 55. Preferably, the end-collars 54 are formed with rounded flanges 56 providing hand-wheels by means of which the shaft 53 may be rotated manually for a purpose as later explained. The shaft 53 is formed with helical thread-grooves 57 and 58 of right- and left-hand pitch or, in other words, the shaft 53 is cross-threaded along substantially its entire length. 85

Slidably longitudinally of the shaft 53 is a sleeve 60 having a rearwardly-extending arm 61, see Fig. 4, constituting a carriage for carrying the supply of yarn Y , the strands of which are to be laid on the surface of the barrel of the squeeze-rolls 35 and 36. The arm 61 terminates at its rearward end in a fork 62 arranged to straddle a cross-rod 63 which extends between the brackets or arms 50, being secured thereto by means of suitable nuts 64. The cross-rod 63 serves as a brace or tie for the arms 50 and preferably carries a tube or sleeve 65 which forms a bearing for the fork 62 of the arm 61, see Fig. 4. The sleeve 65 is usually made of brass to prevent rust or corrosion. Projecting upwardly from the arm 61 is a rod or standard 66 having its lower end bent into an eye 67 which is fastened to the arm by means of a bolt 68. The rod 66 is bent at substantially right-angles 110 at its upper end to provide a spindle 69 for rotatably supporting the yarn-cop or package Y . The cop or package Y is preferably of cylindrical shape, wound with multiple strands of yarn laid in a cross-wind to render the package self supporting without the use of spool flanges. If preferred, however, a spool may be used in place of the cylindrical cop or package Y . Usually the package Y is wound on a cylindrical wooden tube T having an axial bore for receiving the spindle 69 on which the cop turns. The spindle 69 may be set at a slight angle to the horizontal so that the package will maintain its position thereon by gravity with the 115 120 125 130

end of the tube T bearing against the upright portion of the rod 66. A peripheral groove *t* is cut in the periphery of the projecting end of the tube T to adapt it to receive a cord or thong 70 of leather or the like looped over the tube and bearing a weight 71 at its end to cause it to act as a friction-brake to control the rotation of the package. As shown in Figs. 2 and 4, one end of the cord 70 is fastened in a hole 72 in the rod 66 and the cord leads up over the tube T with the disk-weight 71 suspended from its opposite end.

Fastened to a boss 73 on the under side 15 of the arm 61 is a wire strand-guide 74 held in place by a screw 75. The guide 74 has two branches 76 and 77 formed at their ends with loops or pigtailed through which the strands *y* lead as they draw down to the 20 squeeze-roll. The upper branch 76 of the guide directs the strands *y* from the periphery of the package Y across the top of the screw-shaft 53 and thence they lead down through the pigtail on the other 25 branch 77 to feed them on to the barrel of the squeeze-roll.

The sliding sleeve 60 is formed with a slot 78 at its center adapted to receive a crescent-shaped follower 79, see Figs. 2 and 30 4, which engages with the thread-grooves 57 and 58 of the screw-shaft 53. The follower 79 is carried by a plunger-pin 80 which is 35 slideable in a bearing 81 fastened to a boss 82 on the top of the arm 61 by means of a screw 83. A helical spring 85 surrounding the plunger 80 between its bearing 81 and the follower 79 acts to press the latter downward to maintain it in engagement with the threads of the screw-shaft 53. The top of 40 the plunger 80 is preferably knurled to provide a finger-hold so that the plunger may be pulled upwardly to disengage the follower 79 from the thread-grooves when it is desired to manually adjust the sleeve 60 along the screw-shaft 53. It will be obvious 45 from the above description that when the shaft 53 is rotated the sleeve 60 will be traversed first in one direction and then in the other through the engagement of its follower 50 79 with the thread-grooves 57 and 58; it being understood that when the follower reaches the end of one of the thread-grooves 55 it is guided by the curved portion thereof to turn or swivel in its bearing to direct it into the reverse thread to cause the traverse of the sleeve in the opposite direction, this being a usual arrangement for traverse-mechanisms.

The screw-shaft 53 is driven from the 60 squeeze-rolls by means of the gears 45 and 46 at their ends which are fast on the roll-shafts 39 and 40, as previously explained. It is to be understood that the strand-applying mechanism is adapted for use with 65 both of the squeeze-rolls 35 and 36 and

therefore the driving mechanism for the screw-shaft 53 is adjustable in position so that it may be connected to be driven from either of their respective gears 45 and 46. For this purpose the driving mechanism 70 for the screw-shaft 53 is carried on an adjustable arm 88 which is pivoted to swing about the axis of the screw-shaft, see Figs. 2 and 3.

Referring to Fig. 2, the mounting for the 75 arm 88 comprises a separate hub 89 which is rotatable on the shaft 53. The hub 89 is held longitudinally of the shaft 53 abutting the side of a gear 90 which has its hub 91 secured to the shaft by suitable means such 80 as a set-screw 92. The gear 90 is made in the form of a sprocket to adapt it to be driven by a chain 93 passing over a second sprocket 94. The sprocket 94 is fast on the hub of a gear 95 which is journaled on a 85 stud 96 carried at the end of the arm 88. The gear 95 is adapted to mesh with the gear 45 at the end of the roll 35 in one instance and in the other with the gear 46 on the roll 36, see particularly Fig. 3. The stud 96 90 forming the journal for the gear 95 extends through the arm 88 and screws into a handle 97 which serves as a convenient means for manually shifting the arm 88. The handle 97 is scored with a groove 98 to 95 adapt it to receive a wire-hook 99 which is sprung over the shaft 39 or the shaft 40, as the case may be, to hold the gear 95 in mesh with the respective driving gear on one or the other of the squeeze-rolls 35, 36. 100

Referring now to Fig. 2, the hub 89 is held against the side of the gear 90 by a collar 103 secured to the shaft 53 by suitable means such as the set-screw 104. A portion of the hub 89 is turned down or reduced in 105 diameter at 105 to provide a bearing for a slotted portion 106 of the arm 88, see Fig. 3. As shown in this view the arm 88 is widened throughout substantially half of its length and provided with the longitudinal 110 slot 107 which fits the reduced portion of the hub 89. On the hub 89 is a boss 108 from which extends a rod 109 held therein by means of a set-screw 110 shown in Fig. 3. The arm 88 is provided on its side with 115 a lug or bearing 111 which is bored to receive the rod 109 to adapt it to slide therein. One side of the rod 109 is slotted at 112 and a thumb-screw 113 screwed through the side of the lug 111 is adapted to bind against the slotted portion to hold the rod from 120 sliding in the lug. When the thumb-screw 113 is released the arm 88 may be slid as a whole on its hub 89, whereby to lengthen or shorten the distance between the gear 95 and shaft 53 in accordance with requirements to engage the gear with one or the other of the gears 45, 46. After the gear 95 has been brought into mesh with the 125 driving-gear on the appropriate squeeze-roll 130

the arm is held in its adjusted position by tightening the thumb-screw 113 against the rod 109 to prevent further sliding movement.

In order to compensate for the change in relation between the sprockets 90 and 94 during the adjustment of the arm 88 and the consequent tightening or slackening of the chain 93, I provide an idler-sprocket 114 at the upper end of the arm. The idler-sprocket 114 is journaled on a stud 115 at one end of a lever 116 which is pivoted at 117 to the upper end of the arm 88. A spring 120 is anchored to the arm 88 at 121 with its opposite end connected to the end of the lever 116. The spring 120 acts to rock the lever 116 to maintain the sprocket 114 under tension whereby to take up the slack in the chain 93.

The method of operation of my improved roll-covering means as employed on a slasher section having a plurality of squeeze-rolls is as next explained. For covering the first roll 35 the strand-laying mechanism is arranged as illustrated in Figs. 1 and 2, and shown by dotted lines in Fig. 3. That is to say, the arm 88 is drawn out or lengthened by releasing the thumb-screw 113 and sliding the arm on its hub 89. After the arm has been lengthened sufficiently to bring the gear 95 in mesh with the gear 45 on the roll 35 the thumb-screw 113 is tightened against the rod 109 to hold the arm rigid with its pivot. The hook 99 on the handle 97 is then hooked around the roll-shaft 39, as shown in Figs. 1 and 2, to hold the gear 95 in mesh with the gear 45 at the end of the roll 35. The tape of strands *y* from the multiple-wound package of yarn *X* is then led through the pigtail-guides on the branches 76 and 77, as shown in Fig. 4, and thence drawn down to the barrel of the roll 35 and the ends secured thereto.

It has been stated that the barrel of the roll 35 is usually covered with a strip of felt *f* wound spirally thereof with its ends matched to provide a smooth surface without overlapping seams, but in some cases this felt covering may be omitted. In starting to wind the outer covering of strands on the squeeze-roll the traverse-carriage or sleeve 60 is first adjusted in position at one end of the screw-shaft 53. Usually the winding is started at the right-hand side of the machine, viewed as in Fig. 2, and by lifting the rod or pin 80 to release the follower 79 the sleeve may be slid along the shaft 53 to engage the follower with the end of the screw-threads. This adjustment of the sleeve 60 will bring the strand-guide 74 into position with its pigtail yarn-guides directly over the end of the barrel of the roll 35, the ends of the strands *y* being attached to the barrel at this point. Usually the ends of the strip of felt *f* are attached to the metal barrel of the roll 35

by means of tacks driven into wooden blocks set into holes at the ends of the barrel and the ends of the strands *y* may be secured in the same manner.

When power is applied to the machine 70 through the drive-shaft 16 the pinion 15 will drive the gears 11 and 12 in the direction indicated by the arrow *a* in Fig. 1. The gear 11 will therefore transmit rotation to the gears 9 and 10 on the size-rolls 7 and 8 to turn the latter in the direction indicated by arrows *b*. It has been explained that the squeeze-rolls 35 and 36 are mounted to slide in their bearings 41 and 42 so that their peripheries bear on the surface of the size-rolls 7 and 8 under the weight of the squeeze-rolls. Through this frictional contact between the surfaces of the cooperating size-rolls and squeeze-rolls the squeeze-rolls will be driven in the direction indicated by the arrows *c* in Fig. 1. As the roll 36 is turned in this direction the tape of yarns *y* leading thereto will be wound on to its barrel in the manner illustrated in Fig. 2, and meanwhile, the gear 45 on the squeeze-roll 35 will drive the gear 95 on the arm 88. The gear 95 transmits motion through its sprocket 94 and the chain 93 to drive the sprocket 90 which is fast on the screw-shaft 53. The screw-shaft 52 is thus rotated at a relatively slow rate of speed and the engagement of the follower 79 with its threads causes the sleeve 60 to be traversed therealong. That is to say, when the screw-shaft 53 is rotated in the 100 direction indicated by the arrow *d* in Fig. 1 the follower 79 engaging the left-hand thread-groove 58 on the shaft causes the sleeve 60 to be propelled to the left as viewed in Fig. 2. The sleeve 60 and the 105 yarn-supply carrier will thus be caused to traverse slowly along the screw-shaft 53 to cause the tape of strands *y* to be fed toward the left-hand end of the squeeze-roll 35. The traverse of the sleeve 60 is timed to lay 110 the tape or band of strands *y* in a spiral or helix with the strands closely adjacent and substantially covering the barrel of the roll. The length of the threaded portion of the screw-shaft 53 is so proportioned that 115 when the follower 79 reaches the end of the threads the strand-guide 75 will be just above the end of the roll 35 so that the tape of strands will be laid close up to the end-head or flange 43 of the roll. At this point the follower 79 feeds through the curved end-portion of the thread-groove and is directed into the right-hand groove 57. Therefore, as the shaft 53 continues to turn 120 the sleeve 60 will be carried back in the opposite direction and the strand-guide 74 is thus caused to feed the strands toward the right-hand end of the roll. The strands of yarn or other material may thus be laid 125 on to the barrel of the roll in another layer 130

and the operation may be continued to apply as many layers to the roll as required. When the last layer is completed the end of the tape of strands is cut from the supply and fastened to the roll in any suitable manner.

After the surface covering has been applied to the first squeeze-roll 35, the finishing-roll 36 is covered in the same manner by adjusting the strand-applying mechanism to the position shown in full lines in Fig. 3. For this purpose the arm 88 is shortened by releasing the thumb-screw 113 and sliding the arm on its hub 89. After the gear 95 has been set in position engaging the gear 46 on the shaft 40 of the roll 36 the thumb-screw 113 is tightened against the rod 109 and the hook 99 connected with the shaft 40 to hold the gears in mesh. The tape of yarn strands *y* is then led down to the barrel of the roll 36, secured thereto adjacent one of the end-heads, and the traverse of the sleeve 60 started at the appropriate end of the screw-shaft 53. The turning of the gear 46 with the roll 36 drives the gear 95, sprocket 94 and chain 93 to drive the gear 90 to rotate the shaft 53, and the sleeve 60 is thus traversed in the manner as before described to feed the strands on to the barrel of the roll in as many layers as required.

It has been explained that the copper drum or barrel of the squeeze-roll is preferably first covered with a spirally wound strip of felt or like resilient material before the outer covering of yarn is laid thereover. In some cases, however, where a harder, less flexible covering is desired the yarn may be wound directly onto the metal barrel of the roll without the yieldable base. In either case the method of adjusting the machine and operating it to traverse the strands to lay them on the roll is the same. It is to be understood that the felt base is applied to the roll before the machine is placed in operation for slashing. Usually the machine is driven in low gear and the strip of felt guided on to the roll by hand, and after it has been tacked in place the yarn strands are wound thereover with the machine operating under power and the strands automatically guided by the traverse-means as before explained. The initial covering of strands is usually applied to the roll before the slashing operation is started, but it is to be particularly noted that the outer covering of strands may be renewed at any time during the normal operation of the machine while the slashing operation is taking place. In fact, it is the preferred method to apply the strand covering while the machine is operating to slash the warp passing therethrough.

It has been explained that the warp yarns *w* in the form of a sheet are fed into the machine over the guide-rolls 19 and 20,

thence passed down under the immersion-roll 23 and led up over the first size-roll 7 and then across the top of the second size-roll 8. As the warp is thus drawn through the machine it is immersed in the starch or sizing-fluid S in the tank or vat 3 and as it passes over the rotating-drums or rolls 7 and 8 the squeeze-rolls 35 and 36 bear down against the drums to work the fluid into the yarn while squeezing out all surplus fluid before the warp passes out of the machine. It has been demonstrated that with my improved rolls covered with strands as herein described the action of the rolls on the warp yarns has a very beneficial effect. This is due to the fact that the coils of yarn on the squeeze-roll coincide substantially with the parallel arrangement of the yarns in the warp whereby the surface of the roll conforms more closely to the surface of the warp. The roll is preferably covered with a number of strands approximately equal to the number of yarns in the warp and hence the windings on the surface of the squeeze-roll have a tendency to separate the yarns in the warp and to knead and work the size into the yarns on the sides thereof to effect a more thorough sizing of the warp. Furthermore, the surface of the squeeze-roll, which may be described as more or less corrugated due to its make-up of a large number of strands, has a combined squeezing and combing action on the warp yarns tending to comb out and straighten the fibers and to lay them more smoothly in place, and also a cleaning action to brush off any dirt or foreign matter. Moreover, as the surface of the roll conforms more nearly to the surface of the warp there will be less tendency to flatten the warp yarns and hence the yarns emerge from the sizing process in a smoother, rounder state without being flattened or disturbed in twist.

By applying the outer covering to the roll with continuous strands wound on to its barrel the surface of the roll is made exactly concentric with its axis so that there are no high and low points. This results in a more even pressure of the squeeze-roll on the warp during the continuous rotation thereof, the roll having no tendency to rise and fall as is the case where its periphery is eccentric with respect to its axis.

As another advantage of the present improved roll-covering there are no seams, bunches or protuberances on the surface of the roll as is the case with a roll covered with blankets. Heretofore the common practice has been to recover the roll with a blanket of woven material wrapped therearound. It is obvious that a roll covered with a fabric blanket will not have a surface concentric with its axis and hence the roll will rotate out of true with a rising and falling motion as it bears on the warp. This

causes an uneven squeezing pressure so that the warp is not uniformly treated throughout its entire length. Furthermore, a blanket-wrapped roll has a lapped seam extending across its length formed by the edge of the blanket and consequently each time the roll makes a complete rotation this seam or ridge will leave a mark across the warp. The cross-threads of the fabric blanket are also apt to indent the warp, but with my improved covering there are no ridges, seams, or protuberances liable to mark the yarns being treated.

As a further improvement my present roll-covering is much more economical both in first cost and as regards its durability or wearing qualities. Moreover, it can be applied to the roll without particular skill or expertness on the part of the operator and hence eliminates the chance of poor workmanship. Its use also eliminates the hand labor and time required for manually covering a roll with blankets and effects substantial economies in this respect.

As a still further economy the present improved roll-covering will wear longer than a blanket covering and may be renewed when required without stripping off the worn covering. That is to say, the strand-covering on the roll may be applied while the slashing operation is being carried on so that there is no loss of production due to idle machinery. Both the front-roll and the back-roll may be covered during the operation of the machine, as the invention provides for adjustment of the strand-applying device or traverse-mechanism from one roll to the other as required. It is therefore only necessary to remove the rolls from the machine after long periods of use when the outer covering has been renewed to such an extent that it has entirely filled the space between the end-flanges or spool-heads. This condition occurs only after the inner felt-covering has become worn or hardened to such an extent that it needs renewing, generally at intervals of from six months to a year, dependent upon the time it takes for acid fumes from various compounds used in the size to eat into the surface of the roll.

When this occurs the roll is taken out of the machine and its barrel trued up in a lathe and coated with white lead. This does not necessarily mean that the machine remains idle, however, because a substitute set of rolls may be kept in reserve and applied to the machine while the defective ones are being made ready for recovering.

The improved strand-applying or covering-means is adapted for universal application to practically all types of slashers and starchers and may be applied to use thereon without change in the basic structure of the machine itself.

The improvement is also adapted for other

types of processing machines, such as starch-mangles for starching or sizing fabrics. Such a type of machine is illustrated in Figs. 5 and 6 of the present drawings. In these views 125 designates the side frames of the machine which support the starch-vat or trough 126. A starch-roll or drum 127 is journaled in bearings at the sides of the starch-vat 126 with its periphery submerged in the fluid therein. Above the roll 127 is a squeeze-roll 128 journaled in bearing-blocks 129 which slide in vertical ways 123. Pressure-screws 130 carrying hand-wheels 131 are mounted in swiveled bearings on a pair of levers 132 which are pivoted in bearings 133 mounted at the top of standards 134 rising from the main frame of the machine. Connected to the outer ends of the levers 132 are pendant rods 135 connected by turn-buckles 136 to rods 137 which are swiveled to lower weight-levers 138. The levers 138 carry weight 139 tending to draw the upper levers 132 downward to apply pressure to the screws 130, which, in turn, act through the bearings 129 of the squeeze-roll 128 to cause it to press against the cloth or fabric C passing through the rolls. The cloth C delivers from a roll 140, passes over and under a series of tension-bars 141, and thence draws between the squeeze-roll 128 and starch-roll 127 to a wind-up roll 142. In this type of machine the starch-roll 127 is driven from gearing 143 and through its contact with the squeeze-roll 128 it rotates the latter as the cloth passes therethrough. The squeeze-roll 128 is provided with flanges 144 and at the outer end of its shaft 145 is a gear 146. My improved feed-mechanism for applying the strands to the surface of the squeeze-roll 128 is supported from suitable brackets 147 attached to the sides of the standards 134. The mechanism of the device is identical with that previously described and comprises the arm 88 carrying the gear 95 at its end adapted to mesh with the gear 146 on the end of the squeeze-roll shaft 145. The gear 95 carries the sprocket 94 which drives the gear 90 on the traverse-shaft 53 through the medium of the chain 93.

In this type of cloth-processing machine there is usually only one set of rolls acting on the fabric so that the covering-mechanism does not require to be shifted to cover the different rolls. However, the mechanism is preferably of the same construction as previously described to adapt it to be shifted out of the way when it is not required for covering the squeeze-roll. It is to be understood that in the embodiment of the invention as last described the arm 88 may be rocked to shift its gear 95 away from the gears on the squeeze-roll 128, the arm being suspended by any suitable means while the covering-mechanism remains inoperative.

With some methods of processing textiles, such as in starch-mangles, dyeing and finishing machines, a rubber-covered roll is employed to obtain the required resiliency on its surface. This type of roll requires frequent grinding or turning down to true its surface and as the thickness of the covering is reduced there is a consequent loss of resiliency. With my improved strand-covering the roll does not lose its resiliency during long periods of use and its surface may be renewed when required at much less cost than with a rubber covering. Moreover, the rubber covering is liable to vary in resiliency at different points, that is, to have relatively hard and soft spots due to inequalities in the mixing or vulcanizing of the rubber, so that the yarn-covering is much superior as being substantially uniform in resiliency and also less subject to deterioration from exposure to acid fumes or climatic conditions.

It will be observed that my invention provides a particularly simple and efficient apparatus for the purpose specified which may be adapted to various types of machines and employed as an attachment therefor. It is to be understood that where the covered roll has been herein referred to as a squeeze-roll, this term is to be considered in a broad sense as indicating any type of processing roll or drum. The use of my improved roll-covering or roll-surfacing apparatus provides for applying the covering to the rolls in the machine and operates in a novel manner to produce a covering which has many features of improvement over the ordinary roll-coverings heretofore used.

It is obvious that various modifications may be made in the structure and arrangement of the parts of my improved apparatus without departing from the spirit or scope of the invention. Therefore, without limiting myself to the exact construction as herein shown and described or to the precise steps in the operation of the device as heretofore explained, I claim:

1. In a processing machine, the combination of co-operating rolls between which material passes, of which one is a press roll, and means whereby strand material may be applied to cover the face of said press roll by operating said machine.

2. In a processing machine, the combination of co-operating rolls between which material passes, of which one is a roll presenting a face covered with strand material wound on said roll, and means whereby strand material may be applied to the face of said covered roll as the machine operates on the material passing between said rolls.

3. In a processing machine the combination of a rotating roll over which material draws, a squeeze-roll adapted to bear against the material, and means for laying strand

material on the squeeze-roll as it is rotated from the first roll during the operation of the machine.

4. In a processing machine, the combination of co-operating rolls, of which one is a press roll, and means actuated and controlled by said press roll during the rotation thereof in the operation of the machine for applying strand material in coils to the peripheral surface of said press roll. 75

5. In a processing machine, the combination of co-operating rolls between which material passes, means to drive the rolls to apply a covering to one of them comprising mechanism for feeding strand to lay it in coils on the periphery of the roll during the operation of the machine. 80

6. In a processing machine, the combination of co-operating rolls between which material passes, one a driven roll and the other a press roll having surface contact with the driven roll to be driven by it, means for rotating the driven roll, and strand-laying mechanism actuated and controlled by said press roll for applying strand material in coils to its peripheral surface as said rolls are rotated in the operation of the machine. 85

7. In a processing machine, the combination of co-operating rolls between which material passes, one of said rolls presenting a substantially smooth-faced peripheral surface and the other of said rolls being a press roll in engagement with the peripheral surface of said substantially smooth-faced roll 90 and driven by surface contact therewith, and means whereby strand material may be laid in helical coils on the peripheral surface of said press roll as said rolls are operated in the operation of the machine. 95

8. In a processing machine, a processing roll adapted to bear against the material being treated, and means for treating strand material to form a covering around the periphery of said roll as it is rotated in the operation of the machine, said means comprising a strand feed, means for traveling the strand feed to lay the strand material on the roll in helical coils, and means whereby the traveling means may be operated as said roll is rotated in the operation of the machine. 100

9. In a processing machine, a processing roll adapted to bear against the material being treated, means whereby strand material may be fed to form a covering around the periphery of said roll comprising a strand feed and operating mechanism for said feed, mechanism rotatable synchronously with said roll as said roll is rotated in the operation of the machine and means 115 whereby said respective mechanisms may be thrown into and out of engagement with one another. 120

10. In a machine for processing sheet-materials, the combination of a plurality of 130

processing-rolls, strand-feeding means for feeding textile strands to one of the rolls, means to travel the strand-feeding means longitudinally of the roll to lay the strands in helical coils thereon, and means for connecting the strand-feeding means to operate in connection with any one of the rolls.

11. In a processing machine, the combination of a plurality of processing-rolls, of strand-feeding means for feeding textile strands onto the barrel of a roll, means for adjusting the strand-feeding means into operative relation with the different rolls, and means for traveling the strand-feeding means longitudinally of the rolls.

12. In a processing machine, the combination of a plurality of processing-rolls, gears on said rolls, strand-feeding means for feeding textile strands onto the barrel of a roll, means for adjusting the strand-feeding means into operative relation with any one of the rolls, means for traversing the strand-feeding means longitudinally of the roll, and gearing for driving the traversing means from the gears on the respective rolls.

13. In a processing machine, the combination of a plurality of processing-rolls, strand-feeding means for feeding textile strands onto the barrel of a roll, means for adjusting said strand-feeding means into operative relation with the different rolls, means for traversing the strand-feeding means longitudinally with respect to a roll, a gear on each roll, gearing for driving the traversing-means, and an adjustable arm for connecting said gearing with the gear on any one of the rolls.

14. In a processing machine, the combination of a plurality of processing-rolls, a gear on the end of each roll, strand-feeding means for feeding textile strands onto the barrel of a roll, means to traverse the strand-feeding means, an adjustable arm, gearing on the arm for driving the traversing means and adjustable therewith to connect it with the gears on the different rolls, and means for holding the arm in position with the gearing connected with the respective gear on one of the rolls.

15. In a processing machine, the combination of a processing-roll, a carriage travelable longitudinally of the roll and adapted to carry a yarn supply, means to travel the carriage during the rotation of the roll, and

means on the carriage for feeding the yarn 55 from the supply to lay it in helical coils on the roll.

16. In a processing machine, the combination of a processing-roll, a gear on the end of the roll, a traverse-shaft in parallel relation with the roll, strand-feeding means connected to be traversed from the shaft to lay textile strands helically of the barrel of the roll, an arm pivoted to swing on the axis of the traverse-shaft, and gearing for driving the traverse-shaft said gearing carried by the arm to adapt it to be connected with the gear on the roll. 60 65

17. In a processing machine, the combination of a plurality of processing-rolls, gears 70 on said rolls, strand-feeding means for feeding strand material onto the barrel of the rolls, a traverse-shaft for traversing the strand-feeding means longitudinally of the rolls, an arm swiveled on the traverse-shaft 75 and adapted for longitudinal extension and contraction with respect thereto, a gear at the end of the arm for engagement with the different gears on the rolls, and means connecting the gear on the arm to drive the traverse-shaft. 80

18. In a processing machine, the combination of a plurality of processing-rolls, gears on said rolls, strand-feeding means for feeding strand material onto the barrel of the 85 rolls, a traverse-shaft for traversing the strand-feeding means longitudinally of the rolls, an arm swiveled on the traverse-shaft and adapted for longitudinal extension and contraction with respect thereto, a gear at 90 the end of the arm for engagement with the different gears on the rolls, a sprocket driven from the gear on the arm, a sprocket on the traverse-shaft, a chain connecting the sprockets, and an idler-sprocket for taking 95 up the slack in the chain when the arm is adjusted in length.

19. In a processing machine, the combination of a processing-roll, a carriage travelable longitudinally of the roll, means for supporting a cop of yarn on the carriage, means for feeding the yarn from the cop on the carriage to guide it onto the barrel of the roll, and means for traversing the carriage to deposit the yarn in layers of helical 100 coils to form a resilient covering on the roll. 105

In testimony whereof I affix my signature.

GEORGE J. McGANN.
